UNITED STATES PATENT OFFICE.

EMMA HAGEMEISTER, OF NEW YORK, N. Y.

HAIR WAVER.

Application filed December 3, 1922. Serial No. 678,294.

To all whom it may concern:

Be it known that I, EMMA HAGEMEISTER, a citizen of the United States, and a resident of the city of New York, borough of Manhattan, in the county and State of New York, have invented a new and Improved Hair Waver, of which the following is a full, clear, and exact description.

My invention relates to a hair waver, and 10 more particularly to a hair waver employing electrically heated combs movable relatively to each other to impart a wavy form to the hair.

The general object of my invention is to 15 provide an electrically heated hair waver in which the heating elements for the respective combs are incorporated in the backs of the combs to promote efficiency in the heating of the combs and to facilitate the 20 assemblage of the parts.

A further important object of the invention is to provide a hair waver having means to directly gage the combs as regards their 25 extent of longitudinal movement for producing waves of different lengths.

The more specific object of the invention is to provide a simplified construction.

The nature of the invention and its distinctive features and advantages will clearly 30 appear as the description proceeds.

Reference is had to the accompanying drawings forming a part of this specification, it being understood that the drawings are merely illustrative of one example of 35 the invention.

Figure 1 is a plan view of a hair waver constructed in accordance with my invention;

Figure 2 is a longitudinal vertical section in the plane indicated by the line 2—2 of 40 Figure 1;

Figure 3 is a longitudinal vertical section in the plane indicated by the line 3—3 of Figure 1;

Figure 4 is a transverse vertical section in 45 the line 4—4 of Figure 2; and

Figure 5 is a diagram of the circuit that may be employed.

In carrying out my invention in accordance with the illustrated example, a suitable 50 frame is provided, which advantageously is in the form of a series of longitudinal troughlike elements 10 having vertical flanges 11, the adjacent flanges 11 of adjacent elements 10 being juxtaposed and united by 55 any suitable means, such as welding or braz-

ing. In each element 10 is disposed the hollow back of a metallic comb. The combs and the backs are arranged in two series to move endwise in reverse directions. The backs of one series, three in number in the present example, are designated by the numeral 13; while the tubular backs of the other series of combs, of which there are two shown, are designated 113. Similarly, the combs or teeth of one series of combs are 60 designated by the numeral 14; and the teeth of the other series of combs are designated by the numeral 114. Shanks 20 extend from the backs 13 of one series of combs and connect with a transverse tubular 65 handle bar 15; while the shanks 120 of the other series of comb backs are connected with a transverse tubular handle bar 115. In the flanges of alternate elements 13 slots designated generally by the numeral 12, are 70 formed, the remaining or alternating slots in elements 113 being designated 112.

The slots 12 have terminals 16 and 17 at different elevations connected by an oblique intermediate slot portion 18. Extending 75 transversely and freely through the series of comb backs 13 is a transverse rod 19, said rod being rigid with the frame 10 and extending through the alining slots 12 and 112 at one end of each comb back 13, 113. 80 Similarly, a transverse rod 119 extends transversely through the slots 112 in the opposite ends of the alternating comb backs 113, that is, the comb backs of the other series, said rods 119 extending through slots 85 12 at the adjacent end of the comb backs 13 and being rigid with the frame 10. The frame 10, it will be seen, is shown as made up of trough-like elements or of open top 90 box-like structures laid against one another 95 and held by the rod 19 and the rod 119 which have the form of bolts. Said boxes may also be soldered together at their sides, if desired. The slots 12 and 112 constitute 100 gage means to indicate different longitudinal relative movements of the combs 14. By reason of the slots 112 being the reverse of the slots 12, the one series of comb backs will rise or fall to the same extent as the other comb backs, it being understood that 105 the one series of comb backs is always moved in one direction and at the same time the other comb backs are moved in the opposite direction so that the rods 19 and 119 will 110 be similarly positioned in the respective

slots 12 and 112. If the two rods 19 and 119 are initially in the slot portions 16 at the ends thereof remote from the oblique slot portions 18 as in Figure 3 and the series 5 of comb backs are thus moved reversely relatively to the frame 10, the wave length will depend on the difference between the relative positions of the combs when the hair is put in place and the final position 10 of adjustment. Thus, the relative movements of the combs and the rods cause the slot portions 16 to so shift relatively to rods 19 and 119 that said rods will be disposed at those ends of slot portions 16 15 adjacent the oblique portions 18 instead of the original positions of said rods in those ends of the slots 16 remote from oblique slot portions 18, which change in the positions of the slots and rods determines one 20 wave length according to the length of the slot portions 16, said length being sufficient in practice to produce a wave of a given length by the described relative movements of the rods and slots. A second wave length 25 is obtained by moving the combs relatively to each other and to the rods 19 and 119 not only to an extent corresponding with the length of the slot portions 16 but also sufficient to dispose the rods in the intermediate oblique portions 18 of the slots 12 30 adjacent to the upper terminals 17 of the slots. After a relative movement of the combs to dispose the rods 19 and 119 at the upper terminal of the oblique portions 35 18, said rods are positioned at the juncture of the said oblique portions with the horizontal portions 17, that is to say, positioned at those ends of the upper portions 17 adjacent the oblique portions 18 so that there 40 will be no tendency of the rods and frame to gravitate in the oblique slots 18. A third wave length is obtained by moving the rods 19 and 119 in the upper terminal 17 of the slots. The adjacent slot portions 16, 17, 45 18, being at angles to each other, the extent of movement of the combs is readily determined and indicated. In the movement of the parts when the rods 19 and 119 arrive at any given slot portion, the fact is 50 made apparent to the user of the device since there is an evident and clearly apparent contact by the movement of the rods in the slot portions 16, for example, to the oblique portions 18, the contact with the oblique walls being evident and apparent. Similarly, after the movement to the upper 55 end of the oblique portions the rods 19 and 119, contacting with the walls of the upper portions 17 again makes it evident that the parts have moved a distance represented by the total effective length of the oblique portions 18. Thus, a movement for a given wave length is measured by one or other 60 of the slot portions 16, 17, 18 and when 65 the limit of such movement has been reached

the contact of the rods with the walls of a given slot portion indicate the completion of the movement in a particular slot portion.

Within the tubular comb backs 13 and 113 I provide heating elements, designated 70 respectively 21 and 121 to which lead the conductors 22 and 122, said conductors being disposed in the tubular handle bars 15 and 115 and in the tubular shanks 20 and 120. The wires of the conductors 22 and 75 122 are in circuit with the battery 23, or other source of electricity, as indicated in Figure 5.

The incorporating of the heating elements 21 and 121 within the tubular comb backs 80 13 and 113 facilitates the manufacture and assembly of the parts and makes for efficiency in the heating of the combs 14 and 114.

In the use of the device, a strand of hair 85 8 is laid transversely across the combs of the several series, as shown in Fig. 1, and it will be readily understood that the longitudinal movement of the heated combs will give a wavy form to the strand of hair. 90

I would state in conclusion that while the illustrated example constitutes a practical embodiment of my invention, I do not limit myself strictly to the exact details herein illustrated, since, manifestly, the same can 95 be considerably varied without departure from the spirit of the invention as defined in the appended claims.

Having thus described my invention, I 100 claim:—

1. A hair waver including series of 105 combs, movable longitudinally relatively to each other, said combs having electrical heating elements directly in the backs thereof, tubular cross handles rigid with and 110 communicating with the backs of the combs, and conductors extending through the cross handles and to the heating elements in the 115 respective comb backs.

2. A hair waver comprising a frame, 110 series of combs relatively movable longitudinally in said frame, said frame having transverse rods and said combs having slots 115 through which said rods extend, said slots having terminal members at different elevations and oblique intermediate portions connecting the terminal members, said terminal and intermediate members of the slots constituting distinct gage portions.

3. A hair waver comprising a frame, 120 series of combs relatively movable longitudinally in said frame, said frame having transverse rods near the ends and said combs having respectively near the ends thereof slots through which said rods extend, the slots in one series of combs being the reverse of the slots in the other 125 series.
